UNITED STATES PATENT OFFICE

92,827

DESIGN FOR A CONTAINER OR SIMILAR ARTICLE

Joseph S. Stein, Chicago, Ill., assignor to Lucien Lelong Inc., Chicago, Ill., a corporation of Illinois

Application November 15, 1933, Serial No. 49,730

Term of patent 7 years

To all whom it may concern:

Be it known that I, JOSEPH S. STEIN, a citizen of the United States, and a resident of the city of Chicago, county of Cook, and State of Illinois, have invented a new, original, and ornamental Design for a Container or Similar Article, of which the following is a specification, reference being had to the accompanying drawing, forming a part thereof.

On the drawing:

Figure 1 illustrates an elevation view of the container, or similar article, embodying my invention, and shows a rectangular body having its sides and top enveloped by plates having beveled edges.

I claim:

The ornamental design for a container, or a similar article, as shown and described.

JOSEPH S. STEIN
